CLAIM

The ornamental design for a weight bracelet, as shown and described.

DESCRIPTION

FIG. 1 is a front perspective view of a weight bracelet, showing my new design;

FIG. 2 is a rear perspective view thereof;

FIG. 3 is an enlarged front view thereof;

FIG. 4 is an enlarged rear view thereof;

FIG. 5 is a left side view thereof;

FIG. 6 is a right side view thereof;

FIG. 7 is a top view thereof;

FIG. 8 is a bottom view thereof;

FIG. 9 is a perspective view showing the weight bracelet in an alternate configuration thereof;

FIG. 10 is a perspective view showing the weight bracelet in another alternate configuration thereof;

FIG. 11 is an enlarged detail view of area 11 in FIG. 1 thereof;

FIG. 12 is an enlarged detail view of area 12 in FIG. 1 thereof; and,

FIG. 13 is an enlarged detail view of area 13 in FIG. 2.

The broken lines shown in FIGS. 1-2 and 11-13 depict the bounds of the enlarged views and form no part of the claimed design.

1 Claim, 13 Drawing Sheets
